LINT TRAP

William S. Parrett, Pacific, Mo.

Application June 8, 1951, Serial No. 230,619

3 Claims. (Cl. 183—62)

1

This invention relates to lint traps for use with machines from which lint and fibres are blown, such as clothes driers, and the like.

It is, of course, desirable to catch lint blown from a machine to prevent its being carried out into the open air. Lint traps in common use in the past have generally consisted simply of a basket of screen mesh or the like mounted on the end of the exhaust duct of the machine. The major difficulty with this type of device is that the lint will adhere to the inside surface of the basket until the draft from the exhaust duct is completely cut off. This in turn may lead to over-heating of the machine and, in any event, to its inefficient operation. Also in these lint traps used heretofore, difficulty was experienced in cleaning them while the machine was in operation if, in fact, that could be accomplished at all.

One of the objects of this invention is to provide a substantially self-cleaning lint trap.

Another object is to provide such a lint trap which is simple, efficient, dependable, and cheap. Other objects will become apparent to those skilled in the art in the light of the following disclosures.

In accordance with this invention, generally stated, a lint trap is provided with a lint catching screen mounted within the trap in such a way as to be maintained in lint catching position against the force of the exhaust draft while the screen is free of lint but to be swung open by the force of the exhaust draft when lint has accumulated over a predetermined area of the screen. The force of the draft itself may be utilized to maintain the screen closed against the force of the draft. This may be accomplished by so pivoting the screen that a large area of screen is exposed to the force of the exhaust draft on one side of the pivot while a smaller area of screen offering a relatively great resistance to the exhaust draft is exposed on the other. The resistance of the screen on the short side of the pivot is sufficiently greater than that of the screen of the side of the larger area that the force of the draft against the more highly resistant side is sufficient to keep the screen closed. However, as the "long" side of the screen becomes covered with lint, its resistance to the draft increases to the point where the screen opens with the draft against the force on the short side. Means can be provided for adjusting the resistance of the screen on either side to vary the opening and closing action of the screens. A similar effect can be achieved by restraining the opening of a screen, pivoted at one side of the lint trap, by a spring,

2

with a quick opening detent arrangement to prevent a balance being reached between the force of the spring and the partly open screen. Combinations of the two methods may also be used.

5 A plurality of such screens may be installed in such a way that ordinarily they will not open at the same time. With such an arrangement, no lint will be blown directly from the machine into the air.

10 The screens may be so positioned as to encourage the accumulation of lint progressively from one end of the screen to the other. Furthermore, they may be, and preferably are, so arranged as to use the force of the draft to roll the felted lint from the face of the screen to produce a roll or wad of material which is easily handled.

15 The lint trap may be so constructed as to slide into the exhaust duct and to be removable therefrom as a unit.

20 In the drawings:

Figure 1 is a view in perspective of a lint trap constructed in accordance with one embodiment of this invention;

25 Figure 2 is a sectional view taken along the line 5—5 of Figure 1;

Figure 3 is a view in front elevation of the device shown in Figure 1;

30 Figure 4 is a view in side elevation of the device shown in Figure 1;

Figure 5 is a plan view with the top cut away of the device shown in Figure 1;

35 Figure 6 is a view in perspective of the embodiment of screen for use with this invention, shown in Figures 1—5;

Figure 7 is a view in perspective of another embodiment of this invention; and Figure 8 is a view in front elevation of another embodiment screen for use in this invention.

40 Referring now to the drawings for an illustrative embodiment of this invention, and in particular to Figures 1—6, 1 represents a lint trap designed to slide within a rectangular exhaust duct 2. A tray or box 3 is attached to the outer end of the duct 2 to receive the wadded lint from the trap 1. The trap itself comprises a frame having sides 4, a bottom 5 and a top 6. The top 6 in the embodiment shown is provided with a handle 7 by which the trap may be pulled from the exhaust duct 2. Pivotaly mounted within the frame are two screens 8. The pivots 10, by which the screens are mounted within the frame are secured to the screens 8 in such a way as to divide the screens into a long side and a short side with respect to the pivot. The long side, as

45 50 55

used in the specification and claims, is a side of greater area than the short side. The pivots 10 of the screens 8 are mounted in suitable bearings in the bottom 5 and the top 6. The screens 8 are provided with a frame 9 within which, on the long side of the screen, is wire mesh 11. Within the frame on the short side of the screens is a solid sheet 12, as well as a section of wire mesh 11. When the screens 8 are assembled with the frame their travel in the closing direction is limited by strips 13 and 14. Strip 13 bears against the longer edge of the frame 9 with respect to the pivot 10 while strip 14 on the opposite side of the frame bears against the shorter. The strips 13 and 14 serve as seals as well as stops. A stop 16 may be provided to limit the amount of opening of the screens. It can be seen that the latter function can be accomplished by the proper positioning of the strips 13 and 14 as well. A lip 15 is provided along the front edge of the bottom 5 to limit the sliding of the frame within the exhaust duct 2 and to conduct the rolled, felted lint into the box 3.

A detent 17, as shown somewhat diagrammatically in Figure 6, may be provided. In the embodiment shown in Figure 6, the detent or latch 17 consists of a housing 18, a spring 19, and a ball 20 seating in a slight depression 21 in the top of the frame 9.

In the operation of the embodiment of this invention shown in Figures 1-6 of the drawing, the draft blowing from the exhaust against the solid sheet 12 maintains the screens 8 in a closed position as long as the screens are clean. By setting the screens at an angle with respect to the frame, as shown particularly in Figures 2 and 5, a uniform coating of lint tends to form over the face of the screen from the short side to the long. When the force of the draft on the lint obstructed screen mesh on the long side of the pivot exceeds the force on the other side of the screen, the screen will swing open until it meets the stop 16. The lint, which has a tendency to felt on the surface of the screen will be rolled from the short end of the innermost screen along the entire face of the screen mesh and off, leaving the screen mesh clear and free of lint. When the innermost screen mesh is thus cleaned the force of the draft on the solid sheet 12 closes the screen and the cycle is repeated. Meanwhile the roll of felted lint is urged along the sloping outer screen toward the end of that screen's longer side. When sufficient of the felted lint accumulates on the longer side of the outer screen mesh that screen will also open to allow the felted lint to be blown out. However, the rolls of lint generally have sufficient body so that they do not blow into the room but simply drop into the box 3 provided therefor.

When a latch or detent 17 is used, its detaining force is made less than the differential force on the obstructed screen mesh. The detent-equipped screen opens more abruptly and is less subject to fluttering than the unequipped screen.

Various other forms of detent or latch may be employed for this purpose. For example the detent may consist of a semicircular piece carried by a lever so pivoted in the frame that the wedging action of the piece holds the screen frame when that frame is closed until enough force is applied to the screen to raise the piece. When the screen swings shut after it has been cleaned, the momentum of the screen carries it under the semicircular piece, raising the piece. Also, by extending the lever beyond its pivot on

the side away from the semicircular piece, and putting a slidable weight thereon, the amount of retention of the piece may be varied to suit the needs of the machine, by varying the amount of counter-balancing by the weight of the semicircular piece. Another suitable latch is one similar to a common screen door latch, wherein a U-shaped member, the legs of which straddle the frame, is pivoted at its center and constructed in such a way that sufficient force applied to the inside of one of the legs of the U causes the U to snap in one direction to release the frame, while force applied to the inside of the other leg by the frame snaps the U in the other direction to hold the frame closed.

It may also be found desirable to provide an adjustable plate, which may be fastened to the pivot shaft within the frame, which plate may be moved toward the shorter or longer side to regulate the opening and closing characteristics of the screen. Such a plate is shown at 50 in Figure 8. That plate 50 is provided with slots 51 and wing nuts 52 by which the adjustment can be made. Also the pivot itself may be so mounted on the screen and in the frame so as to be adjustable with respect to the two sections of the screen. Another means for adjusting the relative resistances of the two sides of the screen, shown in Figure 8, is the sliding sheet 12, backed either by the fixed plate 12 or screen mesh. The screen mesh 110 shown in Figure 8 on the short side of the screen is finer than the screen mesh 11 on the longer side. It can be seen that certain of the elements shown in Figure 8 may be dispensed with in any one installation.

In the embodiment of this invention shown in Figure 7 a screen 30 is hinged or pivoted along one edge 31. The screen 30, like the screen 8 in the previous embodiment, is provided with a frame 33 within which is screen mesh 34. A stop 16 performs the same function as that stop in the previous embodiment. Sealing strips, not here shown, may also be used. In the illustrative embodiment shown, the screen is maintained in its closed position by a simple spring ball detent 36. The screen is swung back, after it has blown open and been cleaned, against the force of the exhaust draft, by a spring 37 indicated more or less diagrammatically in the drawing. In this embodiment it is necessary that a detent of some sort be employed. However, the detents or latches described in connection with the embodiment shown in Figures 1-6 may be used satisfactorily.

In the operation of the embodiment shown in Figure 7 the detent 36 maintains the screen closed against the force of the exhaust draft until lint has covered a sufficient area of the screen to a sufficient depth so that the force of the exhaust draft swings open the screen about its pivot and against the force of the spring 37. The spring 37 may be so arranged as to take effect only after the door has escaped the detent 36. The fact that the lint tends to be rolled from the screen from the inner to the outer ends of the screen keeps the screen in a relatively wide open position until the roll of lint passes the outer end of the screen, since the product of the resistance and the distance from the pivot point remains large. When the roll of felted lint leaves the outer end of the screen the screen is swung back against the force of the exhaust draft with sufficient momentum to close against the resistance of the detent.

Even in the embodiment of screen shown in Figure 7 it may be found desirable to provide a

blank sheet, or section of finely woven screen mesh at the pivoted inner end of the screen to facilitate the peeling off of the felted lint from that end.

It can be seen that a plurality of screens like those of the embodiment shown in Figure 7 may be used in the same manner as those of the embodiment shown in Figures 1-6.

Combinations of the two embodiments described are also contemplated wherein a spring (which as in the embodiment shown in Figure 7 may be a coil spring, a torsion bar, or the like) is used in connection with an eccentrically pivoted screen of the first embodiment.

It may be found desirable to cut out the bottom of the frame between the screens and to place a box below that opening. In this way the felted lint from the inner screen may be removed immediately after it leaves that screen while the second screen may function to pick up any unfelted lint which remains. It is, of course, entirely practical to eliminate the outer screen completely in those installations in which the momentary opening of the screen during which the lint is pulled off the screen mesh by the draft, is not undesirable. While a rectangular screen has been illustrated it can be seen that the shape of the screen may be varied in any way desired so long as the screen may be eccentrically mounted to pivot within its frame. It can also be seen that the frame need not have solid sides, top, and bottom but that a skeleton framework is sufficient so long as it provides bearings for the pivots (or support for the hinges in the other embodiment) and sealing means around the screen frame. It can further be seen that no frame at all is needed if the screens are mounted directly in the exhaust duct itself. The only disadvantage of this latter system is that the screens cannot so easily be withdrawn for inspection. The frame has the additional advantage of making the lint trap readily adaptable to existing installations.

Numerous variations of this invention within the scope of the claims will become apparent to those skilled in the art in the light of this disclosure.

Thus it can be seen that a simple, sturdy, efficient, dependable device is provided which is cheap to manufacture and is adaptable to new or old installations, which eliminates the problems of overheating and inefficient operation attending the lint traps of the prior art.

Having thus described my invention, what is claimed and desired to be secured by Letters Patent is:

1. A self-cleaning lint trap for apparatus from which lint is blown through a duct comprising a screen pivoted within said duct for movement between duct opening and duct closing position, detent means for said screen releasable under a predetermined force less than that capable of

being exerted by the draft from said apparatus against the said screen when said screen is completely blocked, and positioned to hold the screen in a duct closing position until the screen is blocked sufficiently to permit the force of said draft to release said detent, and means constantly biasing the screen toward its duct closing position with a force greater than that of the draft against the screen when said screen is clean and less than that exerted by the draft against the screen when said screen is blocked for restoring said screen to its duct closing position when said screen is unblocked.

2. A self-cleaning lint trap mounted within the exhaust duct of apparatus from which lint is blown by a draft of substantial force, comprising a screen mounted in said duct to obstruct the whole cross-sectional area of said duct when said screen is in closed position and pivoted in said duct to swing to an open position at which less than the whole of the cross-sectional area of the duct is obstructed, said screen being eccentrically pivoted to provide on one side of the axis on which it swings a section of smaller area exposed to the force of the draft than the area of the section on the other side of the said axis, the said section of smaller area being positioned on a side of the pivot axis such that the force of the draft upon it tends to move the screen to closed position while the force of the draft upon the section of larger area tends to move the screen to open position, said section of smaller area being constructed to offer sufficiently greater total resistance to the force of the draft than the section of larger area when both are free of lint to permit the force of the draft to maintain the screen closed, but to offer sufficiently less total resistance to the force of the draft than the section of larger area when the section of larger area is blocked with lint to permit the force of the draft to swing the screen to open position.

3. A lint trap of the character described in claim 2 wherein detent means are provided tending to hold the screen in closed position, the construction of the sections of larger and smaller area being such that the force of the draft on the blocked section of larger area is sufficiently greater than the force of the draft on the section of smaller area to overcome the screen-holding force of the detent means.
